CLAIM

The ornamental design for a clip for uniting an electronic device with an extruded heat sink, as shown and described.

DESCRIPTION

FIG. 1 is a perspective view of a clip for uniting an electronic device with an extruded heat sink showing my new design, the broken linework representing outlines of an associated electronic device and a portion of an extruded heat sink, both shown for illustrative purposes in relation to environmental structure and not being part of my claimed design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and

FIG. 7 is a rear elevational view thereof.

FIG. 1

FIG. 2

FIG. 3

FIG. 4

FIG. 5

FIG. 6

FIG. 7
